Primary Examiner — Susan Moon Lee(74) *Attorney, Agent, or Firm* — Brian B. Shaw, Esq.; Harter Secrest & Emery LLP(57) **CLAIM**

The ornamental design for a notched backpack for domesticated animals, as shown and described herein.

DESCRIPTION

FIG. 1 is a right side perspective view of a notched backpack for domesticated animals in an operable configuration in accordance with the present invention;

FIG. 2 is a left side perspective view thereof;

FIG. 3 is a top plan view of the notched backpack for domesticated animals of FIG. 1 in an open, flat orientation;

FIG. 4 is a left side elevation view of the notched backpack for domesticated animals of FIG. 1;

FIG. 5 is a right side elevation view of the notched backpack for domesticated animals of FIG. 1;

FIG. 6 is a rear elevation view of the notched backpack for domesticated animals of FIG. 1;

FIG. 7 is a front elevation view of the notched backpack for domesticated animals of FIG. 1; and,

FIG. 8 is a bottom plan view of the notched backpack for domesticated animals as shown in FIG. 3.

The profile of the domesticated animal and the buckles shown in broken lines are for illustrative purposes only and do not form any portion of the claimed design.
